UNITED STATES PATENT OFFICE

146,159

DESIGN FOR A BATHTUB MAT

Charlie E. Wakefield, Torrance, Calif.

Application February 14, 1946, Serial No. 126,569

Term of patent 3½ years

(Cl. D9—6)

To all whom it may concern:

Be it known that I, Charlie E. Wakefield, a citizen of the United States of America, residing at Torrance, in the county of Los Angeles and State of California, have invented a new, original, and ornamental Design for a Bathtub Mat, of which the following is a specification, reference being had to the accompanying drawing, forming part thereof.

I claim:

The ornamental design for a bathtub mat, as shown.

CHARLIE E. WAKEFIELD.
